[57] **CLAIM**

The ornamental design for a pocketed placemat, as shown and described.

DESCRIPTION

FIG. 1 is a top perspective view of a pocketed placemat showing my new design;

FIG. 2 is a top plan view thereof;

FIG. 3 is an end elevational view thereof, the opposite end being a mirror image of that shown;

FIG. 4 is a side elevational view thereof, the opposite side being a mirror image of that shown;

FIG. 5 is a bottom plan view thereof;

FIG. 6 is a top perspective view of a second embodiment thereof;

FIG. 7 is a top plan view of the embodiment of FIG. 6; FIG. 8 is a bottom plan view of the embodiment of FIG. 6;

FIG. 9 is a top perspective view of a third embodiment thereof, the bottom being identical in appearance to that of the first embodiment;

FIG. 10 is a top perspective view of a fourth embodiment thereof, the bottom being identical to that of the first embodiment;

FIG. 11 is a top perspective view of a fifth embodiment thereof, the bottom being identical to that of the second embodiment; and,

FIG. 12 is a top perspective view of a sixth embodiment thereof, the bottom being identical to that of the second embodiment thereof.

The cross-hatching in the views is intended to represent conventional quilting and is understood to uniformly repeat across the surfaces represented.

FIG.1.FIG.2.FIG.3.FIG.4.FIG.5.FIG.6.FIG.7.FIG.8.FIG.9.FIG.10.FIG.11.FIG.12.
